DESIGN FOR A BASE FOR CANDLE LAMPS

Thomas J. Muench, Syracuse, N. Y., assignor to
Muench-Kreuzer Candle Company Inc., Syra-
cuse, N. Y., a corporation of New York

Application September 22, 1933, Serial No. 49,318

Term of patent 3½ years

To all whom it may concern:

Be it known, that I, THOMAS J. MUENCH, a citizen of the United States, residing at Syracuse, in the county of Onondaga, and State of New York, and having his post-office address at 1303 Court Street, Syracuse, New York, have invented a new, original, and ornamental Design for a Base for Candle Lamps, of which the following is a specification, reference being had to the accompanying drawing forming part thereof, in which Figure 1 is an elevation of this base for

candle lamps and Figure 2 is a plan view thereof.

The new ornamental feature resides in the contour and lines of the bowl and legs as shown.

I claim:

The ornamental design for a base for candle lamps substantially as shown and described.

In testimony whereof, I have hereunto signed my name, at Syracuse, in the county of Onondaga, and State of New York, this 8th day of August, 1933.

THOMAS J. MUENCH.
